UNITED STATES PATENT OFFICE.

WILLIAM G. HAWLEY, OF ELMIRA, NEW YORK, ASSIGNOR TO AMERICAN LA FRANCE FIRE ENGINE COMPANY, INC., OF ELMIRA, NEW YORK, A CORPORATION OF NEW YORK.

AUTOMOBILE FIRE-ENGINE.

1,306,760.

Specification of Letters Patent. Patented June 17, 1919.

Application filed January 3, 1917. Serial No. 140,346.

To all whom it may concern:

Be it known that I, WILLIAM G. HAWLEY, a citizen of the United States, and a resident of Elmira, in the county of Chemung and 5 State of New York, have invented certain new and useful Improvements in Automobile Fire-Engines, of which the following is a specification.

This invention relates to automobile fire engines and has for its primary object to provide an improved arrangement of the parts of a fire engine pump with respect to each other and with respect to the chassis of 10 the automobile upon which the pump is carried. The invention contemplates the elimination of vibration due to pumping, in so far as is possible, and the consequent improvement in the operation of the pump. One of the objects of the present invention 15 is to provide an improved arrangement of parts which will effectively counter-balance the inertia of the moving parts. Another object of this invention is to provide an improved arrangement of pumping cylinders 20 and valves in a double action multiplex pump. Another object is to provide an improved construction, combination and arrangement of parts in that type of fire engine pumps with which it may be desirable 25 in some cases to throw a large volume of water at low pressure or at other times a smaller volume of water at relatively higher pressure. More specifically stated, my invention contemplates the provision of pumping 30 cylinders of different diameters and suitable and efficient means for operating said cylinders in different combinations. Various minor features and objects of invention will appear in the specification and be pointed 35 out in the appended claims, reference being had to the accompanying drawings, which exemplify my invention and in which:—

Figure 1 is a side elevation of an automobile fire engine pump, constructed in accordance with the principles of the present invention, parts being broken away and parts shown in section;

Fig. 2 is a top plan view of the same;

Fig. 3 is a vertical longitudinal section on 45 an enlarged scale through the crank housing and one of the cross-head guides, parts being shown in elevation;

Fig. 4 is a vertical longitudinal section on 50 an enlarged scale through a cylinder, cross-head and guide therefor, and one of the

valve chambers, parts being broken away and parts shown in elevation;

Fig. 5 is a horizontal section through cylinders, cross-head guides and the upper portion of the crank housing, parts being shown 60 in plan;

Fig. 6 is a horizontal section through the crank housing between the crank shafts and jack shafts, parts being shown in plan;

Fig. 7 is a combined vertical section and 65 front elevation of the crank housing;

Fig. 8 is a front elevation of the pump, parts being broken away and parts shown in section;

Fig. 9 is a vertical longitudinal section of 70 the lower portion of the crank housing, parts being shown in elevation;

Fig. 10 is a front elevation of one of the crank shafts removed.

According to the embodiment of my invention shown on the drawings, the chassis of the automobile includes the side bars or beams 1. Referring first to Fig. 5, a plurality of low pressure cylinders 2, and high pressure cylinders 3, the latter being of 80 smaller diameters than the former, are arranged abreast on parallel axes extending longitudinally of the chassis and in a common horizontal plane. Reciprocably mounted in said cylinders are pistons 4, 4 and 5, 5, 85 which are connected by piston rods 6, 6 and 7, 7 with cross-heads 8, 8 and 9, 9, said cross-heads reciprocating in cylindrical cross-head guides 10, 10 and 11, 11. The cross-heads 8, 8 are connected by rods 12—12 with 90 wrist pins 13' carried by a crank shaft 13 which is journaled in ball bearings 14. A counterweight 72 is carried by each crank-shaft to counterbalance the effects due to inertia of the crank-shaft and reciprocating 95 parts connected thereto. Each of said crank-shafts is journaled at opposite ends in bearings 73 and 74 carried by the crank-case. The cross-heads 9, 9 are connected by rods 15 with a crank shaft 16, journaled in ball 100 bearings 17. It will be seen therefore, that these crank shafts are rotatable separately for driving the high pressure pistons independently of the low pressure pistons. Keyed to the crank shaft 13 is a spur gear 18 which meshes with a spur gear 19 (see Fig. 7) which is geared to a jack shaft 20 journaled in ball bearings 21 and 22. The crank shaft 16 has keyed thereto a spur gear 23 which in a similar manner meshes with 110

a spur gear 24 (see Fig. 6) on a jack shaft similar to jack shaft 20. Said jack shafts extend through housings 25, the bearings for said jack shafts being housed in the boxes 26. As shown best in Fig. 6, oppositely arranged bevel gears 27 and 28 are keyed respectively to these jack shafts 20. Intermeshing with these bevels 27 and 28 are bevel pinions 29 and 30, which, as shown best 10 in Fig. 9 are freely journaled on a short section 31 of the fore and aft driving shaft from motor to transmission of the automobile. Splined to the shaft section 31, are separately movable clutch elements 32 and 15 33, which are adapted to have interlocking engagement with similar clutch elements 34 and 35, carried by the pinions 29 and 30. Suitable and efficient means for moving the clutch elements 32 and 33 into and out of 20 locking engagement with the clutch elements 34 and 35, are provided by the projections 36 and 37 which are mounted upon reciprocable rods 38 and 39. Referring now to Fig. 9, it will be seen that the rods 25 38 and 39 are adapted to be reciprocated by lever arms 40 and 41 (see Fig. 8), the latter being keyed to a shaft 42 while the former is keyed to a sleeve 43 journaled on the shaft 42. Secured to the shaft 42 is a lever 44, 30 while secured to the sleeve 43 is a lever 45. These levers project laterally beyond the side beams 1 of the chassis and as shown in Fig. 2 are confined to a limited angular movement. Referring now to Fig. 4, each 35 of the cylinders 2, 2, 3, 3 is open at opposite ends into vertically extended chambers 46 and 47. Valves 48 and 49 are adapted to control the inflow of water into said chambers from a suction chamber 50 which is 40 common to all of the vertical chambers 46 and 47 at opposite ends of all of the horizontally arranged pumping cylinders. As shown in Fig. 4, the piston 4 has just completed its stroke to the left during which the 45 valves 48 have been displaced from their seats to admit a flow of water from chamber 50 into the chamber 46. At the same time, the water formerly thrown into chamber 47 has been expelled upwardly through the 50 passages 51 controlled by an outlet valve 52. As the piston 4 moves toward the right, the valves 48 close, the water in chamber 46 being expelled upwardly through a valve 53. It will be seen from this description that 55 there are a pair of outlet valves 52 and 53 leading from chambers 46 and 47 corresponding to the opposite ends of each pumping cylinder. All of these valves 52 and 53 open into a common pressure chamber 54 60 which is surmounted by a pneumatic cushion 55 which maintains a steady flow of fluid from said pressure chamber. By means of this construction and arrangement, an improved hydraulic balance is maintained between the different cylinders by

affording ample means for absorbing the shocks due to the acceleration and checking different columns of water. The cylinders 2, 2, 3, 3 are rigidly connected together and constitute in effect a rigid member extending between the side beams 1 of the chassis. Referring now to Fig. 3, the crank case housing comprises a bottom portion 56, an upper portion 57 which is releasably joined thereto on a plane 58 which extends at an 70 angle to the chassis and passes through the axis of the crank shafts 13 and 16. The cross head guides 10 are open at their ends adjacent the crank shafts but closed at their other ends by inclined walls 58, which have 75 a sliding fit with the piston rods 6, 6 7, 7. Cross head guides 10, 10, 11, 11 therefore constitute closed extensions of the crank housing and adapt the cross-heads to receive proper lubrication from the splash in the 80 crank housing. Ball bearings 14 and 17 are carried by suitable standards which are mounted on the floor 59 of the crank housing. The rigidly united cylinders 2, 2, and 3, 3, are supported by means of flanged 85 plates 70 which rest upon the side bars of the chassis. In Figs. 2 and 8 is shown a cross-bar 60 extending between the side beams 1 of the chassis adjacent the crank case housing. Centrally disposed with respect to the side beams 1 of the chassis is a bracket 61 which is secured to the end wall of the crank case housing by means of the bracket arms 62 (see Fig. 6) which rest upon the lugs 63 which project inwardly 90 from the bracket 61. A deflected plate or lug 64 at the upper edge of the bracket 61, extends over and rests upon the top of cross beam 60. By means of this central support taken in connection with the rigidly connected cylinders 2, 2, and 3, 3, which are supported from the opposite side bars of the chassis, a three-point suspension is provided for the pump. This construction obviates in large measure the twisting strains 100 105 to which a pump or engine on an ordinary frame-work is subjected when the automobile rides over uneven surfaces. In this connection, it will be seen that the rigidly connected cross head guides 10, 10, 11, 11 110 are rigidly connected by substantial columns 65 with the cylinder casting, said columns allowing space for the renewal of the cylinder heads so that the valves may be inspected or removed as desired. The advantages of this improved construction and arrangement in its application to automobiles for fire engine purposes, will be appreciated from the foregoing description. Thus the pump is of the double-acting, multiplex, 120 horizontal piston type, embodying in its preferred embodiment, 4 cylinders arranged side by side with pistons operating fore and aft of the chassis frame. Provision is made 125 whereby the 4 pistons may be operated in 130

pairs, each pair having a separate crank shaft and clutch control so that either pair may be operated singly under conditions which demand half capacity of less, or both 5 pairs may be operated simultaneously under conditions which demand half to full capacity. It will be understood that a single pair of cylinders has sufficient capacity to meet the requirements of a large majority 10 of the fires encountered in general service. In this case, the unused cylinders are held in reserve to be used as necessary. The crank shafts are driven from parallel jack shafts by direct spur gear connections, the 15 jack shafts being driven by bevel gears from a section of the fore and aft driving shaft from motor to transmission in the automobile. The jaw clutches afford means for separately connecting and disconnecting these 20 jack shafts from the fore and aft driving shaft. The crank shafts and other driving mechanism are inclosed in a single dust and oil-proof housing bolted to a casting which forms the cross-head cylinders or guides. 25 This construction, while affording ample lubricating facilities for the reciprocating parts, also contributes to the formation of a rigid unit which is supported at the rear by the bracket which suspends the crank case 30 from the cross-beam 60 at a single point, while the cylinder casting is bolted to the top of the side members of the chassis, thus giving a virtual three point suspension. When the pump is in service, the control 35 clutches are operated by separate levers which are conveniently located within reach of the chauffeur.

I claim:

1. In an automobile fire engine, the combination with the chassis frame, of a transverse truss rigidly connecting the longitudinal side bars of said frame, said transverse truss including pump cylinders arranged 40 on horizontal axes, cylindrical cross-head guides coaxially arranged with said pump cylinders respectively and rigidly united with each other, pistons in said pump cylinders, cross-heads in said cross-head guides and connected to said pistons respectively, and means for reciprocating said cross-heads and pistons. 45

2. In an automobile fire engine, the combination with the chassis frame, of a transverse truss rigidly connecting the longitudinal side bars of said frame, said transverse truss including pump cylinders arranged on horizontal axes, cylindrical cross-head guides coaxially arranged with said pump cylinders respectively and rigidly united with each other, pistons in said pump cylinders, cross-heads in said cross-head guides and connected to said pistons respectively, and means for reciprocating said cross-heads and pistons. 50

2. In an automobile fire engine, the combination with the chassis frame, of a transverse truss rigidly connecting the longitudinal side bars of said frame, said transverse truss including pump cylinders arranged on horizontal axes, cylindrical cross-head guides coaxially arranged with said pump cylinders respectively and rigidly united with each other, pistons in said pump cylinders, cross-heads in said cross-head guides and connected to said pistons respectively, and means for reciprocating said cross-heads and pistons, the common axes of said cross heads and cylinders being arranged 55 in a plane adjacent said chassis frame. 60

3. In an automobile fire engine, the combination with the chassis frame, of a transverse truss rigidly connecting the longitudinal side bars of said frame, said transverse truss including pump cylinders arranged on horizontal axes, cylindrical cross-head guides coaxially arranged with said pump cylinders respectively and rigidly united with each other, pistons in said pump cylinders, cross-heads in said cross-head guides and connected to said pistons respectively, and means for reciprocating said cross-heads and pistons, the common axes of said 65 cross heads and cylinders being arranged in a plane adjacent said chassis frame. 70

3. In an automobile fire engine, the combination with the chassis frame, of a transverse truss rigidly connecting the longitudinal side bars of said frame, said transverse truss including pump cylinders arranged on horizontal axes, cylindrical cross-head guides coaxially arranged with said pump cylinders respectively and rigidly united with each other, pistons in said pump cylinders, cross-heads in said cross-head guides and connected to said pistons respectively, and means for reciprocating said cross-heads and pistons, said pump cylinders and the respective cross-head guides corresponding 75 thereto, being arranged in pairs, and said reciprocating means including a separately operable crank shaft connected with each pair of said cross-heads. 80

WILLIAM G. HAWLEY.
